CLAIM

The ornamental design for a hood, as shown and described.

DESCRIPTION

FIG. 1 is a perspective view of a hood showing my new design in a laid flat position;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a front right side perspective view thereof in an open position; and,

FIG. 9 is a rear view thereof.

The shading shown in the drawings defines the contours of the hood and does not reflect a particular surface ornamentation or material.
